UNITED STATES PATENT OFFICE.

FRANK KECK LUDLOW, OF CINCINNATI, OHIO.

AUTOMATIC FIRE-ALARM AND SPRINKLER SYSTEM.

SPECIFICATION forming part of Letters Patent No. 740,450, dated October 6, 1903.

Application filed March 3, 1902. Serial No. 96,489. (No model.)

To all whom it may concern:

Be it known that I, FRANK KECK LUDLOW, a citizen of the United States of America, and a resident of Cincinnati, in the county of Hamilton and State of Ohio, have invented certain new and useful Improvements in Automatic Fire-Alarm and Sprinkler Systems, of which the following is a specification.

This invention relates to certain improvements in automatic fire-telegraphs, and more especially in that class of such devices which are employed in connection with automatic sprinkler systems for transmitting an alarm to a central station in case of fire; and the object of the invention is to provide means adapted to be actuated by the sprinkler system for transmitting an intelligible signal to a central station in case of fire or in case of other accidental discharge of the sprinkler, most damage in frequent cases being caused by water.

The invention consists in certain novel features of the construction, combination, and arrangements of the various parts of the improved fire-telegraph device, whereby certain important advantages are attained and the device is made simpler, cheaper, and otherwise better adapted and made more convenient for use, all as will be hereinafter fully set forth.

The novel features of the invention will be carefully defined in the claims.

In the accompanying drawings, which serve to illustrate my invention, Figure 1 is a diagrammatic view showing a device embodying my improvements applied for use in connection with a sprinkler system, and Fig. 2 is an enlarged sectional view taken axially through the valve forming part of the controlling means for the device. Fig. 3 is a partial sectional view similar to Fig. 2, but showing the valve in raised position. Fig. 4 is an enlarged sectional view taken through the diaphragm forming part of the controlling means for the device.

As shown in the views, 1 indicates the pipes of the automatic sprinkler system arranged upon the different floors of a building and which may be of any preferred kind.

2 represents a cylindrical shell or valve-casing having its upper and lower ends closed by screw-caps 3 and 5, respectively, the upper cap 3 being formed with a bore or passage

4, affording communication between the interior of the shell or casing and the passage 55 of the pipe system 1, and the lower cap 5 being formed with a passage 6, affording an outlet for said shell or casing, as will be herein-after explained. Packing-rings 7 are arranged at the upper and lower ends of the shell or casing to form a close joint with the caps 3 and 5.

8 indicates a partition extended across the interior of the shell or casing 2 and serving to divide said interior into upper and lower 65 compartments or chambers 9 and 10, respectively, and 11 represents a valve-stem arranged axially within the shell or casing and adapted to play vertically through a central opening in the partition 8. Said partition 8 70 has upon its under side an annular depending flange or boss 12, exteriorly screw-threaded to receive a screw-cap 13, whereby a stuffing box is formed to prevent leakage between the chambers or compartments 9 and 10 of the 75 shell or casing around the valve-stem.

The lower end of the valve-stem 11 is made in reduced diameter and carries a valve 14, adapted when the stem is moved downward within the shell or casing to seat itself upon 80 a valve-seat 15 at the floor of the said shell or casing and encircling the outlet-passage 6, as shown in Fig. 2, whereby the said outlet-passage is kept closed. When the valve-stem 11 is moved upward within the shell or 85 casing to the position shown in Fig. 3, the said outlet-passage 6 is of course opened, so as to provide a free and unobstructed exit from the interior of the shell or casing. A nut 16, held on the screw-threaded and reduced lower end of the valve-stem 11, serves to hold the valve 14 in place thereon.

The upper end of the valve-stem 11 is extended so as to project, when said stem is in its lowest position, above the partition 8, as 95 indicated in Fig. 2, and is also screw-threaded to receive a screw-collar 17, flanged around its upper part, above which collar is held on said stem a valve 20, the edge portions 21 of which are upwardly bent and adapted to fit 100 snugly within the chamber or compartment 9 of the shell or casing, after the fashion of a piston, to prevent the downward passage of air or upward passage of water beyond the valve 20. Above said valve the valve-stem 105 11 carries a disk 18 and a nut 19, serving to

hold said valve in place upon the stem in the operation of the device.

When the valve-stem 11 is in lowered position, as shown in Fig. 2, the under side of 5 the valve 20 fits flush upon an annular valve-seat 22, extended around the walls of the shell or casing above the partition 8; but when the said valve-stem is moved upwardly within the shell or casing said valve 20 is 10 lifted off of said valve-seat to the position shown in Fig. 3, and thereby a free annular passage 23 is formed within the shell or casing 2 and around the valve-stem for the upward passage of water within the shell or 15 casing. To limit the vertical movement of the valve-stem 11, the lower end of said stem above the valve 14 is formed with an external screw-thread to receive a collar 24, which by engagement against the underside 20 of the stuffing-box cap 13 arrests the upward play of the valve-stem. The said collar may be adjusted along the stem by reason of the spiral nature of the screw-threads thereof, and in this way the valve-stem may be permitted 25 to play farther or less far in an upward direction in the shell or casing 2.

26 represents a water - supply pipe connected with the main water-supply pipe 26' of the sprinkler system and connected with 30 a water-inlet 25, opening into that portion of the upper chamber or compartment 9 which is between the valve-seat 22 and the partition 8, and 27 indicates a port leading from the upper part of the chamber or compartment 9 and above the valve 20 when the valve-stem is in lowered position, said port 35 27 being connected by a coupling 28 with an air-pipe 29, to be hereinafter referred to.

30 indicates a port leading into the chamber or compartment 10 at the base of the shell or casing 2, said port 30 being also connected by a coupling 28 with said air-pipe 29.

The air-pipe 29 is connected with the interior of a shell or casing formed of two flanged 45 parts 31 and 32, between which are held the edges of a diaphragm 33, of rubber or equivalent elastic material, said diaphragm being extended across the interior of the said shell or casing and being adapted to be pressed upwardly, as shown in Fig. 4, by the tension of the air within the hollow of the shell or casing below the diaphragm, which air is supplied under pressure by way of the air-pipe 29. Above the diaphragm is a head or disk 50 34, held on the lower end of a stem 35, adapted to play vertically in a passage formed in an upward extension or sleeve 36 of the upper member 32 of the shell or casing, the upper extremity of said stem having a flattened 55 head or enlargement 37, upon which is engaged a bent and rounded spring 38, extended down from the under side of a lever 39, pivoted on an upright arm 40 at one side of the shell or casing, the opposite or free end of 60 said lever 39 being provided with a segment-shaped part 41, the outer convex face of which is adapted for contact with the upper bent end 65 of

43 of a contact-arm 44, suitably supported adjacent to the shell or casing. The convex face of the segmental part 41 of lever 39 is 70 also provided with notches or recesses 42, adapted as the said part 41 is moved past the contact-arm to break the contact with said arm 44.

With the contact-arm 44 is connected one 75 wire or conductor 45 of an electric circuit which includes a generator and an announcer 47 of any preferred kind, this latter being arranged at the central station at which the intelligible signal or alarm is to be given. 80 The other terminal of said electric circuit is formed of a wire or conductor 46, connected with the lever 39, through which the current flows to the contact-arm 44 and wire 45, as will be readily understood. 85

In automatic sprinkler systems as ordinarily constructed the pipes of which the system is composed are normally filled with compressed air, which acts by its superior tension or pressure to prevent the entry of water 90 through the pipe 26 into the pipes of the system from a water-supply pipe with which the system is also connected.

In the operation of the device constructed according to my invention the superior air-pressure within the system 1 of pipes is also exerted within the upper part of the upper chamber or compartment 9 of the shell or casing 2 and serves to hold the valve 20 normally pressed downward upon its seat 22, so that 100 the water from the water-supply pipe 26 cannot rise above said valve 20. Said air-pressure is also exerted through the upper air-port 27, which in this position of valve 20 is left free, as shown in Fig. 2, and through the 105 air-pipe 29 underneath the diaphragm 33, so that the stem 35 is kept normally pressed upward above the diaphragm shell or casing, as shown in Fig. 4, so that the lever 39 is supported with the notched portion of its segment 41 above the bent end of the contact-arm 44. The escape of air from the pipe 29 in this position of the parts is prevented by the valve 14, which when the valve 20, with its stem 11, is moved downward seats itself 115 upon the valve-seat 15 and closes the outlet-passage 6, so that no air is permitted to escape from the pipe 29 through the coupling 28 and port 30. Each horizontal pipe is provided with a sprinkler having a fusible plug. 120 In case of fire these plugs are fused and the air-pressure within the pipe system is immediately lessened, so that it becomes inferior to the pressure exerted beneath the valve 20 by the water from the supply-pipe 26, whereupon the superior water-pressure is exerted 125 to lift said valve off its seat 22, opening the annular passage 23 and causing said valve, together with its stem 11, to move upward within the casing until the stop - collar 24 130 comes into engagement with the stuffing-box cap 13 and prevents further movement of the parts. As the valve 20 is lifted in this way its upwardly-directed side walls 21 travel up

in close contact with the walls of the shell or 5 casing 2 and serve to close the port 27, so as to prevent the flow of any air from the chamber or compartment 9 through the air-pipe 29 into the chamber of the diaphragm casing or shell. The valve 14 at the lower end of the stem 11 is likewise lifted off of its seat 15 when the valve 20 is moved upward, so that the outlet 6 is freed and the excess of air-pressure within the pipe 29 and in the chamber below the diaphragm is immediately relieved, and said diaphragm is permitted to 10 fall either by its own elasticity or by reason of the weight of the parts exerted thereon, 15 the segment-shaped portion 41 of lever 39 falling down to cause the upper bent end of the contact-arm 44 to traverse the convex surface of the same, whereby the circuit including the annunciator 47 is opened and 20 closed to transmit an intelligible signal or call to the central station, at which said annunciator is located. As the valve 20 is moved upward by the pressure of the water-supply exerted beneath it the stop-collar 24 on the 25 valve-stem 11 will come into engagement with the under side of the stuffing-box cap 13, so as to stop and prevent any farther movement of said valve upwardly and to hold the port 27, leading from the chamber or compartment 30 9 to the air-pipe 29, closed, so that no pressure may be exerted beneath the diaphragm 33 to maintain the same in raised position. In this way it will be seen that the call or alarm is transmitted to the central station 35 immediately upon the fall of the air-pressure in the sprinkler system below the predetermined point and its transmission is not liable to be delayed in case the air-pressure falls very slowly. As soon as the air-pressure falls below the water-pressure the 40 valve 20 is permitted to rise and in its movement cut off the diaphragm-chamber from the pipe system, valve 14 meanwhile opening outlet 6 for exhaust of pressure from the 45 chamber. It will also be obvious from the above description that the device may be employed in connection with various systems and is not limited for use to any particular type of sprinkler system, and it will also be 50 obvious that the device is capable of considerable modification without material departure from the principles and spirit of the invention, and for this reason I do not wish to be understood as limiting myself to the precise form and arrangement of the several 55 parts of the device as herein set forth.

My improvement permits of the arranging of a number of signals in a single electric circuit, thereby connecting a series of signals 60 (which may or may not be located) in different houses directly with the central office.

Having thus described my invention, what I claim, and desire to secure by Letters Patent, is—

65 1. The combination of an electric circuit including an annunciator, a sprinkler system, a valve-casing in communication with said

system, a second casing in communication with said valve-casing, a diaphragm in said last-named casing, said diaphragm being normally under pressure from the said system, a valve slidably mounted in the said valve-casing, means whereby the said valve is actuated by the water to cut off the air-pressure from the said diaphragm, means for exhausting the air from the said diaphragm-casing, and means actuated by the said diaphragm for breaking and making the said circuit. 70 75

2. The combination with a sprinkler system, of a casing normally in communication therewith, a suitably-mounted valve for shutting off communication between the said casing and sprinkler system, an electric circuit including an annunciator, a member movably mounted in the said casing and actuated by pressure from the said system, means for exhausting the air from said casing, a stationary arm, and a movable arm included in said circuit, said movable arm having its free end 90 enlarged and provided with a series of notches, substantially as and for the purpose specified. 80

3. The combination with the sprinkler system, of a valve-casing in communication therewith, a second casing normally in communication with the said valve-casing and the sprinkler system, a valve arranged in the said first-named casing, an alarm, means arranged in the said last-named casing and actuated by the pressure therein for controlling the 95 alarm, and means whereby as the pressure in the said sprinkler system is decreased the water will actuate the said valve thereby cutting off the communication between the said sprinkler system and last-named casing, and 100 a second valve actuated by said first-named valve for permitting the air in the last-named casing to exhaust. 105 110

4. The combination with the sprinkler system, containing air under pressure, of a valve-casing in communication therewith, a water-supply in communication with both the sprinkler system and the said valve-casing, a valve arranged in the said casing and normally actuated by the pressure from the 115 sprinkler system, a second casing normally in communication with the said valve-casing and sprinkler system, a means arranged in the said last-named casing controlled by the pressure from the sprinkler system, an alarm 120 controlled by the said last-named means, and an exhaust-port for the said last-named casing controlled by the said valve, whereby as the said air-pressure is decreased the water will cut off the communication between the 125 said system and second-named casing and open the exhaust-port thereof, substantially as described.

Signed at Cincinnati, Ohio, this 26th day of February, 1902.

FRANK KECK LUDLOW.
